(57) **CLAIM**

The ornamental design for the adjustable countertop protector, as shown and described.

DESCRIPTION

FIG. 1 is an exploded perspective view of an adjustable countertop protector;

FIG. 2 is a perspective view of the adjustable countertop protector with its pieces connected in a first configuration; FIG. 3 is a front view of the adjustable countertop protector as shown in FIG. 2;

FIG. 4 is a back view of the adjustable countertop protector as shown in FIG. 2;

FIG. 5 is a left-side view of the adjustable countertop protector as shown in FIG. 2;

FIG. 6 is a right-side view of the adjustable countertop protector as shown in FIG. 2;

FIG. 7 is a top elevation view of the adjustable countertop protector as shown in FIG. 2; and

FIG. 8 is a bottom elevation view of the adjustable countertop protector as shown in FIG. 2.

FIG. 9 is a perspective view of the adjustable countertop protector shown in FIG. 1 with its pieces connected in a second configuration.

FIG. 10 is a front view of the adjustable countertop protector as shown in FIG. 9;

FIG. 11 is a back view of the adjustable countertop protector as shown in FIG. 9;

FIG. 12 is a left-side view of the adjustable countertop protector as shown in FIG. 9;

FIG. 13 is a right-side view of the adjustable countertop protector as shown in FIG. 9;

FIG. 14 is a top elevation view of the adjustable countertop protector as shown in FIG. 9; and,

FIG. 15 is a bottom elevation view of the adjustable countertop protector as shown in FIG. 9.

The dash-broken lines shown in the figures represent portions of the adjustable countertop protector that form no part of the claimed design.

The break lines shown in the figures are not part of the claimed design and represent that no particular length is claimed.

1 Claim, 11 Drawing Sheets
